REFRIGERATOR, INCLUDING A CABINET PROVIDED WITH A SLIDING DOOR

Daniel L. Kaufman and Robert E. Fleming, Dayton, Ohio, assignors to General Motors Corporation, Dayton, Ohio, a corporation of Delaware

Application March 7, 1946, Serial No. 652,494

11 Claims. (Cl. 62—89)

1

This invention relates to refrigeration and particularly to refrigerator cabinets and doors employed to close an opening providing access to the interior of such cabinets.

Ordinarily a door providing access to a food storage chamber of a refrigerator cabinet is fully opened each time an article is to be removed from the chamber irrespective of the size of such article. Frequent manipulation of the door to fully open position results in a material loss of refrigeration due to the escape of cold air from the chamber over the entire area of its access opening, normally closed by the door. For this reason we propose to utilize a slidable door for normally closing the food storage chamber access opening of a refrigerator cabinet, which door, when moved, will uncover only a portion of the total area of the opening and afford access to one part or another part of the chamber while at the same time maintaining one of the parts of the chamber access opening closed. In practicing our invention the amount of cold air escaping from the refrigerated chamber is reduced and the refrigerating system associated with the cabinet is rendered more efficient.

An object of our invention is to provide an improved refrigerator cabinet and to increase the efficiency of a refrigerating system associated therewith.

Another object of our invention is to provide a door for normally closing a single access opening leading to the food storage chamber of a refrigerator cabinet which door may be moved in a plurality of directions for uncovering one portion or another portion only of the total area of the access opening.

Another object of our invention is to provide a single slidable door for closing the access opening of a food chamber of a refrigerator cabinet which can be moved horizontally in either of two directions relative to the access opening for alternately uncovering different portions of the access opening while at the same time having a part thereof which cooperates with an evaporator within the chamber and forms the sole means of maintaining another portion of the opening closed.

A still further object of our invention is to provide a slidable door for the access opening of a refrigerator cabinet which when moved to un-

2

cover a portion of the opening will be returned automatically to its normal closed position so as not to permit the door to remain in open position too long.

Further objects and advantages of the present invention will be apparent from the following description, reference being had to the accompanying drawings, wherein a preferred form of the present invention is clearly shown.

10 In the drawings:

Fig. 1 is a front view of a refrigerator cabinet having a door arranged in accordance with the present invention mounted thereon;

Fig. 2 is a view similar to Fig. 1 and shows the door moved toward one side of the cabinet;

Fig. 3 is another view similar to Fig. 1 and shows the door moved toward the other side of the cabinet;

Fig. 4 is a sectional view of the refrigerator cabinet taken on the line 4—4 of Fig. 1 and diagrammatically shows a refrigerating system associated with the cabinet;

Fig. 5 is a broken view of a front position of the refrigerator cabinet with certain elements thereof removed to more clearly illustrate the door mounting;

Fig. 6 is a view similar to Fig. 5 and shows the door moved to one side of the cabinet;

Fig. 7 is an enlarged fragmentary sectional view taken on the line 7—7 of Fig. 1 showing the mounting of the door on upper and lower tracks;

Fig. 8 is an enlarged fragmentary sectional view taken on the line 8—8 of Fig. 5 showing one of the ball bearing door mounting rollers;

Fig. 9 is an enlarged fragmentary sectional view taken on the line 9—9 of Fig. 5 showing part of the door cushioning device; and

Fig. 10 is a sectional view taken on the line 10—10 of Fig. 8 showing a part of the door-returning device.

Referring to the drawings, for illustrating the present invention, we have shown in Fig. 1 thereof a refrigerating apparatus comprising a cabinet 10 having a plurality of outer sheet metal panels 45 or the like 11 and an inner liner 12 (see Fig. 4) forming the food storage chamber 14 within the cabinet. Insulating material 16 is disposed between the panels 11 and liner 12. The front wall of cabinet 10 has an opening 17 therein 50 which provides access to the chamber 14. A door

18 mounted on cabinet 10, in a manner to be hereinafter more specifically described, normally closes the chamber access opening 17. A closed refrigerating system is associated with the cabinet 10 and includes a refrigerant compressing and liquefying unit which may be housed in the lower part of the cabinet and an evaporator 21 mounted in the chamber 14. Evaporator 21 is preferably of the embossed double sheet metal wall type and is in the form of a large plate which cooperates with walls of the chamber 14 to divide the interior thereof into two compartments 14a and 14b. Shelves may be mounted in any suitable or desirable manner on either side of the vertically disposed evaporator 21 and within the compartments 14a and 14b for supporting bottled beverages or other food products. The evaporator 21 has an edge, or is provided with an extension 22, which projects outwardly through the opening 17 and cooperates with the door 18 to retard circulation of air between the compartments 14a and 14b. The refrigerant compressing and liquefying unit of the refrigerating system is diagrammatically shown in Fig. 4 and includes an electric motor 24 which drives, through suitable belt and pulley connections, a compressor 26. Compressor 26 communicates with the evaporator 21 by way of a conduit 27. Any suitable control device (not shown) may be employed for causing starting and stopping of motor 24 and consequently compressor 26 as is conventional in the art. Refrigerant evaporated in evaporator 21 causes the evaporator to cool and circulate air within the chamber 14 and compartments 14a and 14b. The evaporated refrigerant is drawn into the compressor through the conduit 27 whereupon it is compressed and forwarded under pressure, through a conduit 28, to a condenser 29. The compressed refrigerant is cooled and liquefied within the condenser 29 and flows into a receiver 31. Liquid refrigerant is directed from receiver 31, through a conduit 32, back to the evaporator 21 for re-evaporation therein. Any suitable or conventional expansion device or restrictor (not shown) may be employed for controlling the flow of liquid refrigerant into the evaporator 21.

In the present disclosure the door 18 is mounted on cabinet 10 for sliding movement toward one side and/or toward the opposite side of the cabinet. Door 18 may be of any suitable or desirable construction and is provided about its sides with a seal element 36 (see Fig. 8) which sealingly engages the front of cabinet 10 around the chamber access opening 17 to prevent the escape of cold air from the chamber 14. Upper and lower tracks 37 and 38 respectively (see Figs. 5 and 7) are secured to the front wall of cabinet 10 by a plurality of screws 39. Lower track 38 is provided with elongated openings 41 (see Figs. 5 and 6) for the screws 39 and which openings permit adjustment of the tracks relative to one another for proper mounting and operation of the door 18. The top edge of door 18 has an L-shaped metal member 43 secured thereto by screws or the like 44 (see Figs. 5, 6 and 7). Member 43 has brackets 46 welded or otherwise suitably secured thereto and these brackets together with the members 43 form supports for studs or bolts 47 upon which ball bearing rollers 48 are mounted. The construction and mounting of these rollers will be more clearly described in a description of the rollers associated with the lower track 38. A removable cover plate 49 (see Fig. 7) is secured to the cabinet 10 in any suitable

or desirable manner for concealing the upper track 37, L-shaped member 43, rollers 48 and the screws or bolts 44. The bottom edge of door 18 has a metal member 51 secured thereto by screws or bolts 52 (see Figs. 5, 6, 7, and 8). Brackets 53 welded to member 51 form with this member supports for studs or bolts 54 upon which are mounted rollers 56. Each of the rollers 48 and 56 include a ball bearing member 57 (see Fig. 8) upon which the part forming the rollers 48 and 56 is secured in any desirable or conventional manner. This part which forms the rollers 48 and 56 has a groove 59 provided therein for receiving and fitting over the track forming edge portion of track members 37 and 38. With the grooves 59 of rollers 48 and 56 fitting over the edge portion of track members 37 and 38, it is obvious that the door 18 is mounted between these track members upon the cabinet for rolling or sliding movement. The upper track member 37 has a V-like portion 58 (see Fig. 5) cut in the edge part thereof upon which the rollers 48 roll for a purpose to be hereinafter described.

Metal member 51, which moves with movement of door 18, has a bracket 61 welded thereto at each lower corner thereof (see Figs. 5, 6 and 8). The brackets 61 have legs 62 directed inwardly toward the front wall of cabinet 10 (see Figs. 7 and 8) for a purpose to be presently described. Another pair of brackets 64 are welded upon the track forming member 38 and cooperate with the bracket 61. Another pair of brackets 64 are welded upon the bottom portion of lower track forming member 38 and cooperate with the bracket 61. These brackets 64 each have outwardly directed legs 66 which overlap and are normally in vertical alignment with the legs 62 on brackets 61. The one edge of each bracket 61 and 64 at each side of the door 18 has a notch 67 cut therein (see Fig. 10) for the reception of a spring supporting member 69. Member 69 straddles the leg portions 62 and 66 of both brackets 61 and 64 and is provided with a depending portion 71 having a hole therein for the reception of a rod to be presently described. A screw 72 passing through the members 69 is threaded into a cage-like element 73 which has ears 74 bent over one or more end coil portions of a large coil springs 75 (see Fig. 10). Thus the spring 75 is held between opposed cages 73 for expansion when either of the brackets 61 is moved away from a bracket 64 upon movement of the door 18. The brackets 61 and 64, members 69, screws 72, cages 73 and spring 75 all cooperate to provide a means or device for returning the door 18 to its closed position after it has been moved therefrom.

In order to prevent the door 18 from moving too fast in its closing movement, under the influence of spring 75 we provide means for cushioning at least the final closing movement of the door. This means, in the present disclosure, includes a metal cylinder or tube 81 secured to a pair of brackets 82 mounted upon the front wall 11 of cabinet 10 (see Figs. 5, 7 and 9). A fitting 83 located intermediate the ends of cylinder 81 is provided with a passage 84 which is controlled or restricted by a needle valve 86 threaded into the fitting and locked therein by a nut 87 (see Fig. 9). The valve 86 has a knurled part below the lock nut 87 for rotating the valve and adjusting the needle thereof with respect to its seat so as to alter the restricted orifice 84 if desired. A pair of pistons 88 and 89 (see Fig. 5) carried on the rods 91 and 92 respectively are

adapted to be reciprocated within the cylinder 81 upon sliding movement of door 18. One rod 81 passes through the hole in the depending part 71 of the spring supporting member 69 at the one side of the front of cabinet 10 and the other rod 92 passes through the hole in the depending part 71 of member 69 located at the other side of the front of the cabinet. Bushings 93 and 94 are secured in spaced apart relation upon rod 81 one on each side of the member 69 and other similar bushings 95 and 96 are secured upon rod 92 one on each side of the other member 69. A removable cover plate or panel 97 is detachably secured to the front of cabinet 10 in any suitable or desirable manner to conceal member 51, rollers 58, brackets 61 and 64, spring 75, cylinder or tube 81 and other elements associated with the spring 75 and with the cylinder 81. Pistons 88 or 89 move freely toward the open ends of cylinder 81 but, due to the orifice air outlet 84, movement of either piston toward the center of the cylinder will be restricted. In other words the cylinder and the pistons therein form a pump similar to a bicycle tire pump.

The door 18 normally closes the entire area of the chamber access opening 17, as is shown in Fig. 1 of the drawings and can be moved to either side of the cabinet 10 to uncover a portion only of the total area of opening 17 while at the same time providing the sole means of closing another portion of the area of the access opening. While the door is in closed position the door seal element 38 is out of cooperation with the extension member 22 on the front edge of evaporator 21 and therefore some air will circulate between the compartments 14a and 14b. Movement of door 18 toward the left hand side of cabinet 10, as shown in Figs. 3 and 6 of the drawings, will cause legs 62 of the one bracket 61, secured to the lower left hand corner of the door, to move the one spring supporting element 69 in a direction toward the left hand side of the cabinet. This movement of door 18, element 69 and screw 72 causes this screw to pull on cage 73 and thereby stretch the spring 75 lengthwise. In addition, movement of this element 69 along piston rod 81 picks up the bushing 93 and causes the piston 88 to move in a direction outwardly of cylinder 81 (see Fig. 6). Full movement of door 18 to the left hand side of the cabinet also causes the upper right hand roller 48 to drop into the V-like undercut portion 58 provided in track 37. The single door 18 will, by virtue of the roller resting in undercut portion 58 of track 37, remain in open position to uncover that portion of the area of access opening 17 leading to the compartment 14b. While in this open position the door 18 has a part thereof which forms the sole means of closing the other portion of the access opening 17 leading to compartment 14a. That portion of the seal element 38 along the right hand side of door 18 cooperates with the evaporator 21 or its extension 22 to prevent the escape of cold air from compartment 14a when compartment 14b is opened. If the door 18 is not moved entirely to the left hand side of cabinet 10 the spring 75 will, due to its being stretched, immediately return the door to its normal closed position when the door is released. However, if door 18 is fully opened so that roller 48 rests in the undercut portion 58 of track 37, as shown in Fig. 6 of the drawings, then a slight jar or starting movement is required to move the roller out of the undercut 58 whereupon the door will be returned to its normal closed posi-

tion under power of the energy stored in spring 75. Closing movement of door 18 causes the spring supporting element 69 to move to the right along rod 81 until it strikes the bushing 94 thereon, and then the rod 81 is moved to the right or into the cylinder 81. Piston 88 on rod 81 is therefore moved toward the center of cylinder 81 and this movement of piston 88 tends to compress air within the cylinder. The orifice 84 in fitting 83 restricts the escape of air from cylinder 81 and this retards movement of piston 88 to its normal position within the cylinder and consequently the simple air pump described cushions the action of spring 75 and the final closing movement of door 18.

Movement of door 18 toward the other side of cabinet 10 or to the right, as shown in Fig. 2 of the drawings, to uncover that portion of the access opening 17 leading to compartment 14a will cause the elements located at the lower right hand corner of the door to come into play or to operate in the same manner as is described in the description of operation of the elements on the left hand side of the door. In this right hand movement of door 18, bracket 61 carried on plate 51 and both of which move with the door, element 69 will be moved to the right to stretch spring 75 and the lower end 71 of element 69 will engage the bushing 96, secured to rod 92, and move the piston 89 toward the open end of cylinder 81 to render the air pump effective for cushioning the closing movement of door 18. In moving door 18 to the right it may, if access to compartment 14a is desired for any length of time, be moved fully open so that the left hand upper roller 48 will rest in the undercut 58 of track 37. If this be the case the door 18, instead of immediately returning to its closed position under the power of the stretched spring 75, will have to be manually started toward closed position whereupon the spring 75 will close same. Spring 75 is adjustably maintained between brackets 64, by the spring supports 69 bearing against these brackets, under a slightly stretched tension, so as to insure that door 18 will be centralized with respect to the cabinet side walls. Since the brackets 61 and also the spring supports 69 move with movement of door 18 the spring 75 is uniformly stretched irrespective of the direction of movement of the door. The normal closed position of door 18 retains the air pump or door cushioning device in a neutral position so that movement of the door either to one side or to the other side of the refrigerator cabinet will render one of the pump pistons effective when the door is moved by the spring 75 to closed position.

In view of the foregoing it will be seen that we have provided an improved door arrangement for a refrigerator cabinet in which a single door normally closes the entire area of the food chamber access opening and when moved in a first direction uncovers at least one side of the access opening while forming the sole means of closing the other side thereof, and when moved in a second direction uncovers the said other side of the access opening while forming the sole means for closing the said one side thereof. By providing a single door which slides in two different directions within the confines of the width of the refrigerator cabinet the cabinet can be installed in any location without danger of the door interfering with other objects of furniture or appliances located adjacent the cabinet. The improved door, by uncovering a portion only of the

chamber access opening at any one time and by closing another portion of the chamber, conserves cold air within the refrigerated chamber.

While the form of embodiment of the invention as herein disclosed, constitutes a preferred form, it is to be understood that other forms might be adopted, as may come within the scope of the claims which follow.

What is claimed is as follows:

1. In a refrigerator, a cabinet having a plurality of walls forming a chamber, said cabinet having an opening in a wall thereof providing access to said chamber, a single door for closing said chamber access opening, a closed refrigerating system associated with said cabinet and including an evaporator mounted in said chamber for cooling air therein, said evaporator cooperating with walls of said chamber to divide the interior thereof into a plurality of compartments, means for mounting said door on said cabinet for sliding movement, said door when moved in a direction toward one side of said cabinet uncovering that portion of said chamber access opening leading to one of said compartments and having a part thereof cooperating with said evaporator and forming the sole means of closing that portion of said chamber access opening leading to another of said compartments, and said door when moved in a direction toward the other side of said cabinet uncovering that portion of said chamber access opening leading to said another compartment and having a part thereof cooperating with said evaporator and forming the sole means of closing that portion of said chamber access opening leading to said one of said compartments.

2. In a refrigerator, a cabinet having a plurality of walls forming a chamber, said cabinet having an opening in a wall thereof providing access to said chamber, a single door for closing said chamber access opening, a closed refrigerating system associated with said cabinet and including an evaporator mounted in said chamber for cooling air therein, said evaporator cooperating with walls of said chamber to divide the interior thereof into a plurality of compartments, means for mounting said door on said cabinet for sliding movement, said door when moved in a direction toward one side of said cabinet uncovering that portion of said chamber access opening leading to one of said compartments and having a part thereof cooperating with said evaporator and forming the sole means of closing that portion of said chamber access opening leading to another of said compartments, said door when moved in a direction toward the other side of said cabinet uncovering that portion of said chamber access opening leading to said another compartment and having a part thereof cooperating with said evaporator and forming the sole means of closing that portion of said chamber access opening leading to said one of said compartments, and means rendered effective by movement of said door in either of said directions for returning the door to its closed position.

3. In a refrigerator, a cabinet having a plurality of walls forming a chamber, said cabinet having an opening in a wall thereof providing access to said chamber, a single door for closing said chamber access opening, a closed refrigerating system associated with said cabinet and including an evaporator mounted in said chamber for cooling air therein, said evaporator cooperating with walls of said chamber to divide the interior thereof into a plurality of compartments, means for mounting said door on said cabinet for sliding

movement, said door when moved in a direction toward one side of said cabinet uncovering that portion of said chamber access opening leading to one of said compartments and having a part thereof cooperating with said evaporator and forming the sole means of closing that portion of said chamber access opening leading to another of said compartments, said door when moved in a direction toward the other side of said cabinet uncovering that portion of said chamber access opening leading to said another compartment and having a part thereof cooperating with said evaporator and forming the sole means of closing that portion of said chamber access opening leading to said one of said compartments, means rendered effective by movement of said door in either of said directions for returning the door to its closed position, and means also rendered effective by movement of said door for cushioning said last named means at least during the final closing movement of the door.

4. In a refrigerator, a cabinet having a plurality of walls forming a chamber, said cabinet having an opening in the front wall thereof providing an access to said chamber, a single door for closing said chamber access opening, a closed refrigerating system associated with said cabinet and including a sheet metal evaporator mounted in said chamber for cooling air therein, said evaporator being vertically disposed within said chamber and cooperating with walls thereof to divide same into a plurality of compartments, said door being mounted on track means disposed above and below said chamber access opening for sliding movement, said door when moved in a first direction uncovering a portion of said chamber access opening leading to one of said compartments and having a part thereof cooperating with said evaporator for closing that portion of said chamber access opening leading to another of said compartments, and said door when moved in a direction opposite said first direction uncovering that portion of said chamber access opening leading to said another of said compartments and having a part thereof cooperating with said evaporator for closing that portion of said chamber access opening leading to said one of said compartments.

5. In a refrigerator, a cabinet having a plurality of insulated walls forming a chamber, a closed refrigerating system associated with said cabinet including a refrigerant translating unit and an evaporator for cooling the interior of said chamber, one wall of said cabinet having an opening therein providing access to said chamber and having other outer cabinet walls directed therefrom, each of two opposed walls of said chamber access opening being spaced a substantial distance inwardly of the cabinet outer wall adjacent thereto, a single door normally closing said opening, said door being mounted for sliding movement along said one cabinet wall intermediate said other outer cabinet walls, said door when moved in a first direction positioning an edge thereof substantially in alignment with one of said cabinet outer walls and uncovering one portion of said chamber access opening, said door when moved in another direction positioning its opposed edge substantially in alignment with the other of said cabinet outer walls and uncovering another portion of said chamber access opening, and said door when moved to either of its said positions having a part thereof covering one of said portions of the opening.

6. In a refrigerator, a cabinet having a plurality

of insulated walls forming a chamber, a closed refrigerating system associated with said cabinet including a refrigerant translating unit and an evaporator for cooling the interior of said chamber, one wall of said cabinet having an opening therein providing access to said chamber and having other outer cabinet walls directed therefrom, each of two opposed walls of said chamber access opening being spaced a substantial distance inwardly of the cabinet outer wall adjacent thereto, a single door normally closing said opening, said door being mounted for sliding movement along said one cabinet wall intermediate said other outer cabinet walls, said door when moved in a first direction positioning an edge thereof substantially in alignment with one of said cabinet outer walls and uncovering one portion of said chamber access opening, said door when moved in another direction positioning its opposed edge substantially in alignment with the other of said cabinet outer walls and uncovering another portion of said chamber access opening, said door when moved to either of its said positions having a part thereof covering one of said portions of the opening, and means rendered effective by movement of said door in either of said directions for returning the door to its said normal closed position.

7. In a refrigerator, a cabinet having a plurality of insulated walls forming a chamber, a closed refrigerating system associated with said cabinet including a refrigerant translating unit and an evaporator for cooling the interior of said chamber, one wall of said cabinet having an opening therein providing access to said chamber and having other outer cabinet walls directed therefrom, each of two opposed walls of said chamber access opening being spaced a substantial distance inwardly of the cabinet outer wall adjacent thereto, a single door normally closing said opening, said door being mounted for sliding movement along said one cabinet wall intermediate said other outer cabinet walls, said door when moved in a first direction positioning an edge thereof substantially in alignment with one of said cabinet outer walls and uncovering one portion of said chamber access opening, said door when moved in another direction positioning its opposed edge substantially in alignment with the other of said cabinet outer walls and uncovering another portion of said chamber access opening, said door when moved to either of its said positions having a part thereof covering one of said portions of the opening, means rendered effective by movement of said door in either of said directions for returning the door to its said normal closed position, and means also rendered effective by movement of said door for cushioning said last named means at least during the final closing movement of the door.

8. In a refrigerator, a cabinet having a plurality of insulated walls forming a chamber, a closed refrigerating system associated with said cabinet including a refrigerant translating unit and an evaporator for cooling the interior of said chamber, one wall of said cabinet having an opening therein providing access to said chamber and having other outer cabinet walls directed therefrom, each of two opposed walls of said chamber access opening being spaced a substantial distance inwardly of the cabinet outer wall adjacent thereto, a single door normally closing said opening, said door being mounted for sliding movement in opposite directions along said one cabinet wall, means for limiting sliding

of said door to prevent its movement beyond said other outer cabinet walls, said door when moved in a first direction uncovering one portion of said chamber access opening and covering another portion thereof, said door when moved in a second direction uncovering said another portion of said chamber access opening and covering said one portion thereof, and means rendered effective by movement of said door in either of said directions for returning the door to its said normal closed position.

9. In a refrigerator, a cabinet having a plurality of walls forming a chamber, said cabinet having an opening in a wall thereof providing access to said chamber, a single door normally closing said chamber access opening, a closed refrigerating system associated with said cabinet and including an evaporator mounted in said chamber for cooling air therein, said evaporator cooperating with walls of said chamber and having means associated therewith and cooperating with the inner face of said door to divide said chamber into a plurality of compartments, means for mounting said door on said cabinet for sliding movement, said door when moved in one direction uncovering that portion of said chamber access opening leading to one of said compartments and cooperating with said means associated with said evaporator to close that portion of said chamber access opening leading to another of said compartments, and said door when moved in a direction opposite said one direction of movement thereof uncovering that portion of said chamber access opening leading to said another compartment and cooperating with said means associated with said evaporator to close that portion of said chamber access opening leading to said one of said compartments.

10. In a refrigerator, a cabinet having a plurality of walls forming a chamber, a closed refrigerating system associated with said cabinet including a refrigerant translating unit and an evaporator for cooling the interior of said chamber, one wall of said cabinet having an opening therein providing access to said chamber, a single door normally closing said chamber access opening, said door being mounted for sliding movement in opposite directions along said one cabinet wall, said door when moved in a first direction from its normally closed position uncovering one side of said chamber access opening and covering the other side thereof, said door when moved in a second direction from its normally closed position uncovering said other side of said chamber access opening and covering said one side thereof, means rendered effective by moving said door in either of its directions of movement for returning the door from either of its moved positions to its said normal closed position, and means rendered effective by moving said door in either of its directions of movement for cushioning said last named means at least during the final closing movement of the door.

11. In a refrigerator, a cabinet having a plurality of walls forming a chamber, a closed refrigerating system associated with said cabinet including a refrigerant translating unit and an evaporator for cooling the interior of said chamber, one wall of said cabinet having an opening therein providing access to said chamber, a single door normally closing said chamber access opening, said door being mounted for sliding movement in opposite directions along said one cabinet wall, said door when moved in a first direction from its normally closed position un-

covering one side of said chamber access opening and covering the other side thereof, said door when moved in a second direction from its normally closed position uncovering said other side of said chamber access opening and covering said one side thereof, holding means securing said door against closure after being moved into either of said directions of movement thereof, and means effective upon release of said holding means for returning the door from either of its moved positions to its said normal closed position.

DANIEL L. KAUFMAN.
ROBERT E. FLEMING.
